UNITED STATES PATENT OFFICE

ARTHUR W. M. DICKINS, OF LONDON, ENGLAND

MANUFACTURE OF METHYL-PARAMIDOPHENOL SULPHATE (METOL)

No Drawing.

Application filed January 29, 1925. Serial No. 5,635.

This invention relates to the manufacture of methylparamidophenol sulphate (metol), and more particularly relates to a method of manufacturing this substance by the glycine process.

The principal aim of my invention is to provide a process of the above character which gives a maximum yield and which may be practiced commercially, yielding expeditiously, and with low cost and expense, a chemical of superior and improved quality.

More particularly my invention includes the provision of an improved method of decomposing parahydroxyphenylglycine (glycine) to a recoverable metol base, and a method which minimizes loss of materials; which permits flexibility in temperatures in its practice; which permits the employment of inexpensive and commercial chemicals; and permits the recovery of the final product by simple and inexpensive methods. Other objects of my invention will be in part obvious and in part pointed out hereinafter.

In its broader aspect my improved process comprises the use of cresylic acid as a means of decomposing parahydroxyphenylglycine (glycine). The cresylic acid and glycine are brought together and subjected to a heat of sufficient intensity and duration to decompose the glycine to recoverable metol base without causing the base to be converted to tar or to evaporate, and the heat being of insufficient intensity and duration to cause decomposition of the cresylic acid. The metol base thus formed in the cresylic acid vehicle is readily recoverable in accordance with well known methods and practices which are obvious to persons skilled in the art.

The following are examples of how my process may be carried out.

Example 1.—Place together in a suitable vessel 5 grs. glycine and 50 grs. cresylic acid, heating at a temperature of 170 to 180 degrees centigrade until there is no further decomposition of glycine. Then dilute the mixture with about 100 c. c. solvent naphtha, and shake out with 50 c. c. water containing 2 c. c. 50° Baumé sulphuric acid. This divides the mixture into two layers, one comprising

the cresylic acid and naphtha. After removing the water layer this is boiled with charcoal, filtered and evaporated to dryness. Then wash the residue with alcohol, and metol, the desired final product, is obtained. The cresylic acid is recoverable according to well known practice.

Example 2.—Place together 10 grs. glycine and 100 grs. cresylic acid, and heat at 170 to 180 degrees centigrade for about three hours. Distil off most of the cresylic acid (90 grs. is sufficient) under 25 inches vacuum, leaving sufficient cresylic acid in the residue to protect the metol base from decomposition. Then take up residue in alcohol and sulphate with 3.5 c. c. 50 degrees Baumé sulphuric acid. Let stand overnight. Then filter and dry. The product so obtained is metol, the desired final product.

Although the process is operative when glycine is added either quickly or slowly to cold cresylic acid, it has been found that the yields are greater when the glycine is added gradually to hot cresylic acid. An extremely high yield has been obtained when the proportion of glycine to cresylic acid was one to twelve and the temperature permanently fixed at 185 deg. C. and the glycine added evenly over a period of two hours.

The metol base is slightly volatile in cresylic acid. The distillate from the cresylic acid distillation should contain about $\frac{1}{3}$ of 1% of its volume of metol base. Pure metol base can be completely distilled under high vacuum without any decomposition, but in the presence of the impurities, which constitute the cause of the 87% yield in the standard decomposition, only $\frac{1}{2}$ (approx.) of the base can be distilled before complete decomposition of the still residue occurs.

As many changes could be made in the above process without departing from the scope of my invention, it is intended that all matter contained in the above description shall be interpreted as illustrative and not in a limiting sense.

What I claim is:

1. A process of the character described, which includes making a mixture of cresylic acid and parahydroxyphenylglycine having

the proportion of one part of parahydroxyphenylglycin to approximately twelve parts of cresylic acid and heating the mixture sufficiently to decompose parahydroxyphenylglycin to methylparamidophenol (base) without decomposing the cresylic acid.

2. A process of the character described, which includes decomposing parahydroxyphenylglycin to methylparamidophenol (base) in a protecting medium comprising cresylic acid, by heating the parahydroxyphenylglycin to from 170° to approximately 185° C.

3. The process of producing methyl-paraamidophenol which comprises decomposing parahydroxyphenylglycin to methyl-paraamidophenol in a protecting medium comprising a higher phenolic body at a temperature above 170° C.

4. The process of producing methyl-paraamidophenol which comprises decomposing parahydroxyphenylglycin to methyl-paraamidophenol in a protecting medium comprising a cresol at a temperature above 170° C.

5. The process of producing methyl-paraamidophenol which comprises decomposing parahydroxyphenylglycin to methyl-paraamidophenol in a protecting medium comprising cresylic acid at a temperature above 170° C.

6. The process of producing methyl-paraamidophenol which comprises decomposing parahydroxyphenylglycin to methyl-paraamidophenol in a protecting medium comprising more than ten parts of a higher phenolic body for every part of parahydroxyphenylglycin.

7. The process of producing methyl-paraamidophenol which comprises decomposing parahydroxyphenylglycin to methyl-paraamidophenol in a protecting medium comprising more than ten parts of a cresol for every part of parahydroxyphenylglycin.

8. The process of producing methyl-paraamidophenol which comprises decomposing parahydroxyphenylglycin to methyl-paraamidophenol in a protecting medium comprising more than ten parts of cresylic acid for every part of parahydroxyphenylglycin.

9. The process of producing monomethyl-para-amidophenol sulphate which comprises decomposing parahydroxyphenylglycin to monomethyl-para-amidophenol in the presence of a higher phenolic body and then agitating the reaction mixture with a solution containing a quantity of sulphuric acid sufficient to convert the monomethyl-para-amidophenol to monomethyl-para-amidophenol sulphate, said solution being a solvent for monomethyl-para-amidophenol and a non-solvent for monomethyl-para-amidophenol sulphate.

10. The process of producing monomethyl-para-amidophenol sulphate which comprises

decomposing parahydroxyphenylglycin to monomethyl-para-amidophenol in the presence of a higher phenolic body and then agitating the reaction mixture with an alcoholic solution containing a quantity of sulphuric acid sufficient to convert the monomethyl-para-amidophenol to monomethyl-para-amidophenol sulphate.

This specification signed this 31st day of December, 1924.

ARTHUR W. M. DICKINS.
